UNITED STATES PATENT OFFICE.

STEPHEN BALKWILL, OF CLEVELAND, OHIO.

RAILWAY-CROSSING.

1,233,437.

Specification of Letters Patent. Patented July 17, 1917.

Application filed November 28, 1914. Serial No. 873,452.

To all whom it may concern:

Be it known that I, STEPHEN BALKWILL, a citizen of the United States, residing at Cleveland, in the county of Cuyahoga and State of Ohio, have invented a certain new and useful Improvement in Railway Crossings, of which the following is a full, clear, and exact description.

As a substitute for the old style railway crossings which were made up of short sections of rolled rail, properly arranged and spiked to the ties, there is now being much used a crossing which is made of cast manganese steel formed with intersecting parallel pairs of grooves or flangeways in its top surface adapted to receive the wheel flanges, and located adjacent to the surfaces on which the wheels roll.

It has been found however that, in use, these cast crossings are liable to break, the line of fracture being, in part at least, through the thin walls which form the bottoms of the flangeways.

The object of this invention is to provide a railway crossing built up of cast sections which are so constructed, arranged and connected, that the resulting structure will have all of the desirable qualities of the previously known cast steel crossings, but will be less liable to breakage, and which, if breakage occurs, may be easily and quickly repaired at comparatively little expense.

The invention involves as one fundamental characteristic, the employment of the crossing of members having the necessary flangeways formed partly by one of said members and partly by the other, and in connecting the members together by horizontal bolts. This feature of construction imparts to the crossing flexible qualities such as will permit a sufficient yielding of the weight-supporting member on one side of the flangeway relative to the member which does not support weight on the other side of the flangeway, so that these two members are not likely to be broken apart. Another desirable feature lies in the construction of said two connected members which together form the flangeways with interlocking edges so arranged that they will relieve the connecting bolts of some of the strains incident to the passage of a car or train over the crossing.

This invention consists in the construction of a combination of parts shown in the drawing, and hereinafter described and

pointed out definitely in the appended claims.

In the drawing Figure 1 is a plan view of a railway crossing embodying the invention in the best form known to me; Fig. 2 is a plan view of one of the so-called side members thereof; Fig. 3 is a plan view of one of the corner members thereof; Fig. 4 is a vertical section on line 4-4 of Fig. 1; Fig. 5 is a vertical section on line 5-5 of Fig. 1; Fig. 6 is a vertical section on line 6-6 of Fig. 1.

Referring to the parts by reference characters, 10 represents one of the side members. There are four of these; and in a right angle crossing they may be exactly alike, and, therefore, interchangeable.

12 represents a corner member. There are four of these; and in a right angle crossing they may be exactly alike, and, therefore, interchangeable.

Each side member 10 consists of two parallel outwardly extended arms 10^b, and an intermediate bar 10^a which is integrally connected at its ends with said arms 10^b. When the four side members are assembled, the four intermediate bars 10^a are arranged at right angles to one another, with their mitered ends in contact, and with all of the arms 10^b extending outward from the central frame formed by said four intermediate bars.

The four corner members 12 are then placed as shown, each with its two arms 12^b respectively parallel and in contact with the adjacent arms 10^b of two side members. The contacting edge of each arm 10^b is formed with a groove 10^c. Each contacting edge of an arm 12^b is formed with a tongue 12^c which fits the groove 10^c.

The portion 10^a of each member 10 is what I term a tread portion, in that it is adapted to have the periphery of the car wheel roll along it.

Similarly, the top surfaces upon the angular corner pieces 12 are formed as tread portions. Therefore, when the members 10 and a corner piece 12 are laid to form a crossing, the tread portions of the pieces 10 form continuations of the tread portions of the pieces 12.

In the top surface of each tongue-carrying arm 12^b, and close to and parallel with its tongue-carrying edge, a one-sided groove 110 or flangeway 12^d is formed. When any two arms 10^b 12^b are assembled, as shown, the

arm 10^b will form one side of the said groove or flangeway. These arms 10^b 12^b are connected together by horizontal bolts 14 which preferably go through bosses 12^e on the under side of the arms 12^b.

The angularly extending arms 10^b of the pieces 10 are formed so as to have the function of guard flanges, and these arms co-operate with the arms of the pieces 12 to 10 form a flange-way for a flanged car wheel.

In the top surface of the intermediate bars 10^a the grooves or flangeways 10^c are formed so as to be alined with and to form the connection link between two alined 15 flangeways 12^d.

In the inner edges of the intermediate bars 10^a the grooves 10^c are formed. These receive the arms of angle bars 15 which fit them. Bolts 16 passing through these angle

20 bars and the adjacent intermediate bars securely fasten the members 10 together.

The members 10 and 12 are formed with foot flanges 10^f 12^f to enable them to rest squarely upon, and to be secured to the supporting railway ties.

25 The preferable manner in which these crossings may be properly arranged with respect to the track is shown in the drawing. The outer parts of the arms 12^b are recessed 30 along their inner edges and so shaped that the rolled track rail sections 17 will fit the recess with their top surfaces in alinement with those top surfaces 12^e of the arms 12^b which are just outside of the grooves 12^d.

35 The inner edge of each arm 12^b is formed to fit against the side of the rail 17 between the ball 17^a and the foot flange 17^b thereof. A filler piece 18 is fitted between said track rail 17 and the arm 10^b; and these four 40 parts are then connected by horizontal bolts 19.

For convenience particularly in the claims I have referred to those portions of the crossing with which the tracks co-operate as 45 the approaches of the crossing.

Technically, of course, sometimes a car 50 may approach or leave by the parts which I term approaches, and I do not intend to limit myself by the use of the term. However, it is believed that the portion referred to will be well understood in the use 55 of the term.

As shown, and above described, the crossing 60 is a right angle crossing. It may, however, be adapted to be used intermediately of track rails which cross each other at some other angle, by merely constructing the members 10 with their arms 10^b at the desired angle to the intermediate bars 10^a, and by forming the corner members 10 with their arms 10^b in the proper angular relation to each other.

65 There will be such a degree of flexibility between any two connected members that when cars are being run over the crossing,

and the weight of such cars is being supported by one only of said two members, they may yield slightly, wherefore breakage is not likely to occur. But, if the breaking does occur, the crossing may be repaired 70 by removing the broken part and substituting a new part therefor.

Having thus described my invention, what I claim is:—

1. In a railway crossing, the combination 75 of members, each having an arm with a tread portion and an arm element formed as a guard, and other members forming a corner only having elements each of which forms a tread portion, each arm element 80 before mentioned engaging with an element forming a tread portion above the base of said member, thereby to form a wheel flange-way.

2. In a railway crossing, the combination 85 of members, each having an arm with a tread portion and an arm formed as a guard, and other members forming corners only, each having tread portions, which engage with and are secured to the arms formed as 90 guards of the first mentioned members to form intersecting flange-ways.

3. A railway crossing, comprising two members, each having angularly extending arms, one arm of each member having a 95 tread portion, the other arm of each member formed as a guard, and a third integral member forming a corner only having angularly extending arms, each of which arms is formed with a tread portion that engages 100 with and is secured to the arms formed as guards of the first mentioned members to form flange-ways.

4. A railway crossing, comprising members, each having an arm with a tread portion, and an arm formed as a guard, and a distinct member having a corner portion formed integral, and portions extending therefrom which form tread portions that engage with and are secured to the arms 110 formed as guards upon the first mentioned members to form flange-ways.

5. In a railway crossing, the combination 115 of a plurality of members which when assembled have intersecting grooves formed in their top surfaces, each approach of the crossing comprising oppositely disposed parts having a groove formed in and by both of said parts, said parts engaging each other only along a surface of contact which 120 is above the bottom of the member engaged so that the engaging member receives its support in part from the member engaged and is in part independently supported.

6. A railway crossing having approach 125 portions, an approach portion being formed in two parts, said parts co-operating to form a wheel flange groove, the said parts engaging along a surface of contact at which the parts are secured together, said surface be- 130

ing above the bottom of the member engaged, whereby the engaging member is supported in part by the engaged member and in part independently supported whereby the parts have a certain amount of flexibility in their connection.

7. In a railway crossing, the combination of two members, each having a flangeway formed therein, there being angular extensions upon said members, each of said angular extensions having a partially formed flangeway therein and other members which coöperate with the angular extensions to form intersecting completed flangeways.

15. 8. In a railway crossing, the combination of two members, each having a flangeway formed therein, there being angular extensions upon said members, each of said angular extensions having a partially formed flangeway therein, an angular member having arms, which arms coöperate with adjacent extensions and form a completed flangeway.

9. A railway crossing, comprising four side members, each consisting of two arms which are parallel with each other and extend in the same direction and an intermediate connection with the two arms in which connection a flangeway is formed and four corner members, each having two arms in which arms a partial flangeway is formed, the said members being arranged and connected in such position that the two arms of a corner member engage with arms on each of two adjacent side members, there being formed in the surface of the structure so produced two pairs of parallel intersecting flangeways.

10. A railway crossing comprising four side members, each consisting of two arms which are parallel with each other and extend in the same direction, and an intermediate bar which is integrally connected at its ends with said two arms, and four corner members each having two integral arms,—said members being arranged, and connected together, in position such that the two arms of each corner member contact respectively with an arm on each of two adjacent side members,—and there being in the surface of the structure so produced two pairs of parallel intersecting flangeways.

11. A railway crossing comprising four side members, each consisting of two arms which are parallel with each other and extend in the same direction, and an intermediate bar which is integrally connected at its ends with said two members and which likewise has its ends mitered,—the mitered ends of said four intermediate bars being placed in contact,—angle bars each engaging and connected with the under edges of two adjacent intermediate bars,—and four corner members each having two integral arms which are arranged outside of and in

parallel contacting relation to the arms of two side members, said contacting arms being all connected together,—and there being in the surface of the structure so produced two parallel pairs of intersecting flangeways.

12. A railway crossing comprising four side members, each consisting of two arms which are parallel with each other and extend in the same direction, and an intermediate bar which is integrally connected at its ends with said two members and which likewise has its ends mitered,—the mitered ends of said four intermediate bars being placed in contact,—angle bars each engaging and connected with the inner edges of two adjacent intermediate bars, and four corner members each having two integral arms which are arranged outside of and in parallel contacting relation to the arms of two side members, said contacting arms being all connected together,—and there being in the surface of the structure so produced two parallel pairs of intersecting flangeways, part of said flangeways being formed with one side only and in the arms of the corner members adjacent to the edges thereof, whereby the adjacent arms of the side-members form one side of the flangeways.

13. A railway crossing having corner-members formed with separably and yieldingly jointed sections having guard-rail sections formed thereon, the joints intersecting the wheel-flange grooves in said members.

14. A railway-crossing having its corner-members formed of jointed sections with guard-rail sections formed thereon and extending therefrom, the joints of said sections intersecting the wheel-flange grooves in said members and being yielding, and corner-pieces in the angles between adjacent guard-rail sections.

15. A railway-crossing having corner-members formed of jointed sections with guard-rail sections formed thereon and extending therefrom, the joints of said sections intersecting the wheel-flange grooves in said members and being yielding, and corner-pieces in the angles formed by adjacent guard-rail sections, the opposing guard-rail sections and corner-pieces forming confining means for the end-portions of track-rails between them.

16. A railway-crossing having corner-members formed of obliquely-jointed sections, the joints intersecting the wheel-flange grooves in said members, guard-rail sections on said jointed sections, and corner-pieces in and fitting the angles formed by adjacent guard-rail sections, the opposing guard-rail sections and sides of the corner-pieces corresponding in length and forming confining means for the end-portions of track-rails between them.

17. A railway-crossing comprising straight

- one-piece cast rail-sections having oblique ends meeting in the corner-members of the crossing to form yielding joints intersecting the wheel-flange grooves in said 5 members.
18. A railway-crossing comprising straight one-piece cast rail-sections having oblique ends meeting in the corner-members of the crossing to form joints intersecting 10 the wheel-flange grooves in said members, and guard-rail sections on the opposite ends of each of said rail-sections.
19. A railway-crossing comprising straight one-piece cast rail-sections having oblique 15 ends meeting in the corner-members of the crossing to form joints intersecting the wheel-flange grooves in said members, and guard-rail sections on the opposite ends of each of said rail-sections, and corner-pieces in the angles formed by adjacent 20 guard-rail sections, the guard-rail sections and corner-pieces forming confining means for the end-portions of track-rails between them.
20. In a railway crossing the combination 25 of members each having an arm with a tread portion and an arm element formed as a guard, and other members forming a corner having elements each of which form a tread portion, each arm element before mentioned 30 engaging with an element forming a tread portion above the base of said member thereby to form a wheel flangeway, one of the engaging elements being formed with a depression 35 above the base thereof, and the other being formed with a projection which cooperates with the base.
21. A railway crossing comprising members each having an arm with a tread portion and an arm formed as a guard, and a 40 distinct member having a corner portion formed integral and portions extending therefrom which form tread portions that engage with and are secured to the arms formed as guards upon the first mentioned 45 member to form flangeways, the said engaging tread portions and arm portions having the one a depression and the other a projection which engages in the depression, the parts being secured together whereby there 50 is secured a limited flexibility between the parts.
22. A railway crossing having approach portions, an approach portion being formed in two parts, said parts coöperating to form 55 a wheel flange groove, the said parts engaging along a surface of contact at which the parts are secured together, one of said parts being formed with a projection above the base thereof, the other of said parts being 60 formed with a depression above the base thereof, the projection engaging in the depression whereby the engaging member is supported in part by the engaged member and in part independently supported, there- 65 by permitting a limited amount of flexibility in the connection.

In testimony whereof, I hereunto affix my signature in the presence of two witnesses.

STEPHEN BALKWILL.
